UNITED STATES PATENT OFFICE.

CHARLES L. STOKES, OF LOS ANGELES, CALIFORNIA.

METHOD OF SUPPLYING FUEL TO INTERNAL-COMBUSTION ENGINES, &c.

1,288,266.

Specification of Letters Patent. Patented Dec. 17, 1918.

Application filed January 12, 1917. Serial No. 141,948.

To all whom it may concern:

Be it known that I, CHARLES L. STOKES, a citizen of the United States, residing at Los Angeles, in the county of Los Angeles, 5 State of California, have invented new and useful Improvements in Methods of Supplying Fuel to Internal-Combustion Engines, &c., of which the following is a specification.

This invention relates to methods of supplying fuel to internal combustion engines and the like; and particularly to a method for lifting and supplying liquid fuel to an internal combustion engine. It is the object of this invention to provide a simple 10 and effective method of lifting liquid fuel from a low level tank and of supplying the fuel for the use of an internal combustion engine, the lifting and supplying of fuel being accomplished by the suction of the 15 engine.

The method herein described is broadly claimed in my Patent 1,230,832 granted June 19, 1917, which latter was based on my Australian Patent 16,357 filed May 21st, 1915. 20 My present method involves certain improvements over the method there disclosed and it involves particularly the lightening of the rising fuel column by the admission to the same of a restricted quantity of air not only 25 at a low level point but also at a higher level so as to facilitate the venting of the elevated chamber.

For this purpose I illustrate in the drawings a typical apparatus in which my 30 method may be carried out efficiently. Although there are several different forms of apparatus in which the method may be practised, as shown in my Patent 1,230,537 issued June 17, 1917, the apparatus illustrated herein suffices to show how the method 35 may be carried into actual practice, said apparatus being claimed in my companion application 134,137, filed November 29, 1916. The method includes the lifting of liquid 40 fuel from a low level tank to a high level service reservoir by applied suction of the engine. Air is admitted to the rising fuel, so as to lighten the rising column of fuel and so 45 as to carburet the air. That air is then drawn into the engine by the engine suction; and the lifted fuel is then formed into a carbureted mixture with more air, which 50 carbureted mixture is drawn into the engine along with the first mentioned carbureted 55 air. As an important feature of the present invention the air is admitted at a plurality

of spaced points in the rising column, so that the column is lightened not only at a low level point but also at points thereabove so that there will be a greater lightening 60 of the column at the top than at the extreme lower end. The accompanying drawing illustrates a typical form of apparatus; and in these drawings Figure 1 is a view showing the essential features of the apparatus; 65 Fig. 2 is an enlarged section showing the connection of fuel lifting line to the main tank; Fig. 3 is an enlarged section showing the construction of the fuel lifting line; and Fig. 4 is an enlarged section showing a preferred arrangement of service reservoir and carbureter. I have shown the service reservoir and carbureter made as an integral unit; but this may or may not be the case, 70 as may be desired. 75

In the drawing the numeral 10 designates a main low level tank having an air vent at 11 to admit atmospheric pressure to the liquid fuel contained therein. At 12 there is a connection to the fuel lifting pipe 13; 80 and this connection is made so that air may be admitted into the lower end of the pipe, if so desired. For instance, I provide a nozzle 14, controlled by a suitable needle valve 15; and the air may be drawn through the 85 nozzle 14 by the movement of the fuel through the passage 16. This air enters through a pipe 17 whose upper end is above the highest level of fuel in the tank 10. By proper manipulation of valve 15, the proper 90 amount of air may be admitted at the nozzle 14 to mix with the fuel entering the pipe 13. The fuel, with its contained air, is drawn up through the pipe 13 and finally passes at 20 into service reservoir 21. This service reservoir 21 may be built integrally with the carbureter, as illustrated. The mixed fuel and air entering the chamber passes through a baffle 22 which prevents the fuel from being drawn directly to the suction port 23 before 100 the fuel and air have had an opportunity to separate. The fuel settles in the bottom of the reservoir 21 while the air is drawn out through the suction port 23. This suction port 23 connects at 24 with the suction 105 air passage 25 of the carbureter. Passage 25 connects with intake manifold 26 of the engine 27; so that the suction of the engine is applied, through the suction port 23, directly to the upper part of the service reservoir 21, to create and maintain a partial 110 vacuum therein and to draw into the engine

the air which has risen through the pipe 13 with the fuel. A float 19 is mounted upon an arm 18 pivoted at 28; and a valve 29 is connected loosely, at 30, to the arm 18; this 5 valve 29 serving to close suction port 23 when the float 19 rises when there is a maximum amount of liquid fuel in reservoir 21. The valve 29 is of such size, that the suction through port 23 will hold the valve 10 closed, when it is once seated; so that the float may fall through a short distance, due to the looseness of connection at 30, before its weight will be placed upon the valve 29 to cause the valve to be opened again.

15 At 36 I provide any suitable check valve to prevent back flow of fuel from the carbureter chamber 31 to the service reservoir 21. This carbureter chamber 31 feeds the fuel nozzle 32 in the suction air passage 25. The 20 chamber 31 has an air vent 33; and may be provided with a small float raised valve 34 mounted upon the float 33. It is a function of this float merely to close the air vent 33 should the carbureter be tipped out of normal position so far that the fuel would tend to run out of the vent. The action of float 15 19, keeping the liquid level uniform in chamber 21, acts also to keep the liquid level sufficiently uniform in chamber 31. However, the usual fuel float and float controlled 25 valve may be used in the carbureter chamber if so desired, in order to keep the liquid at a uniform level.

In addition to admitting air at connection 35 12, I may also, and preferably, admit air at different points in lifting pipe 13. For instance, I may provide a small air pipe 40 whose open upper end at 41 is above the liquid level in tank 10, this air pipe 40 extending down through the lifting pipe 13, and being provided with small air holes 42. These air holes are comparatively very 40 small, as it is only necessary to introduce a very small amount of air. For instance, if the internal diameter of pipe 13 is one-quarter inch, then the external diameter of air pipe 40 would be about one-eighth inch and holes 42 would be of about that size made by a No. 64 drill. The holes may be 45 placed in any suitable vertical relation; but at least one of the holes is preferably placed above the normal level of liquid standing in tank 10 and in the pipe 13. For instance, in practice, I may place the holes 42 on the 50 levels indicated by the dotted lines 42^a in Fig. 1. One of the holes 42 is then always above the level of liquid in tank 10; and all of the holes are preferably below the level denoted by the dotted line L—L, which 55 shows the normal level of liquid fuel in the service reservoir 21. When the valve 29 is open and suction is applied to the reservoir 21, and fuel is being lifted through the pipe 13, then air will enter at the connection 12 60 and also at the air openings 42, and this air

will mix with the liquid fuel and progressively lighten the column of liquid being raised, at the same time carbureting said air. This air separates from the liquid in the reservoir 21, and the air is drawn directly through the suction port 23 into the engine intake. (It will be noted that the port 23 connects with the engine intake above the throttle valve 25^a, so that full benefit is obtained of the engine suction). 70 The liquid fuel accumulates in reservoir 21, raising the float 19 and closing the valve 29 when the liquid reaches a predetermined high level. When the suction is cut off, then the mixed column of liquid and air in 80 pipe 13 separates, the liquid falling back down the pipe to the liquid level in tank 10, and leaving at least one of the openings 42 uncovered; so that there is then atmospheric pressure on the liquid in reservoir 21 85 through the uppermost port 42. This atmospheric pressure on the liquid in the reservoir 21 allows that liquid to flow by gravity to carbureter chamber 31, which is also open to atmospheric pressure. When the 90 carbureter has used enough of the liquid fuel to lower the liquid in reservoir 21 sufficiently to open valve 29, the suction is again applied. The carbureter forms a carbureted mixture of air with the liquid fuel 95 drawn from reservoir 21 and from carbureter chamber 31; and this carbureted mixture is drawn into the engine, through manifold 26, along with the carbureted air drawn through the port 23. In the form of apparatus herein described, it is noted that the application of suction to service reservoir 21 is intermittent; and that suction of carbureted air through suction port 23 is correspondingly intermittent. This is a preferred mode of procedure, although it is not necessarily the only mode. (For instance, in my first filed application hereinbefore mentioned, I explain a mechanism whereby the carbureted air is constantly drawn into 110 the engine intake from the service reservoir). This carbureted air, and carbureted mixture made by the carbureter, are drawn together into the engine intake, to make the final mixture which is actually used in the 115 engine. I find, in practice, that although the first mentioned volume of carbureted air is only drawn into the engine intermittently (in this preferred form of device) yet the composition of this comparatively small volume of carburetted air is so nearly the same as that produced by the carbureter as to make no detrimental variation in the final mixture used by the engine. Of course, in a case where such carbureted air is constantly drawn into the engine intake (as hereinbefore referred to) then there is no variation in composition of the final mixture at all. 125

The foregoing description sufficiently ex- 130

plains the means of carrying out my method to make the method fully understood. I do not herein attempt to describe in detail all the different procedures that may be 5 adopted, or all the different mechanisms that may be used; but rather to merely indicate a practical mechanism and to describe the method as it is carried out in that mechanism. And from this description it will be 10 seen that the essential features of the method are as hereinbefore outlined and as now pointed out in the following claims.

Having described a preferred form of my invention, I claim:

- 15 1. The herein described method of lifting and supplying fuel to an internal combustion engine which method consists in raising a liquid fuel to a closed chamber above the level of the source of supply, by inter-
mittent application of the engine suction to
said chamber, lightening the rising fuel by
admitting to the same a restricted quantity
of air at a low level point and also near said
closed chamber but below the level of liquid
25 therein so that air admitted at the latter
point will vent said chamber during the inter-
missions of the engine suction thereby per-
mitting the fuel to flow by gravity from said
chamber, the carbureted air being drawn
30 into the engine by its suction; forming a
carbureted mixture of air and the lifted
fuel; and drawing said carbureted mixture
into the engine along with the first men-
tioned carbureted air.
- 35 2. The herein described method of lifting and supplying fuel to an internal combustion engine, which method includes raising a liquid fuel to a closed chamber above the level of the source of supply by application
40 of the engine suction to said chamber, and

lightening the rising fuel to increasing de-
grees at increasing distances above said
source of supply by admitting to the same
restricted quantities of air at a plurality of
spaced points, one of which is near said 45
closed chamber, and another of which is near
the source.

3. The herein described method of lifting and supplying fuel to an internal combustion engine, which method consists in rais-
ing a liquid fuel to a closed chamber above
the level of the source of supply, by inter-
mittent application of the engine suction to
said chamber, lightening the rising fuel by
admitting to the same a restricted quantity 55
of air near said closed chamber but below
the level of the liquid therein so that air ad-
mitted at the latter point will vent said
chamber during the intermission of the en-
gine suction thereby permitting the fuel to 60
flow by gravity from said chamber.

4. The herein described method of lifting and supplying fuel to an internal combustion engine, which method includes the rais-
ing of a liquid fuel from a low level tank 65
to a closed chamber above the level of said
tank by application of the engine suction to
said column, and lightening the rising col-
umn of fuel to increasing degrees at increas-
ing distances from said tank by admitting to 70
the same restricted quantities of air at a
plurality of spaced points along the column
outside of the tank.

In witness that I claim the foregoing I
have hereunto subscribed my name this 5th 75
day of January, 1917.

CHARLES L. STOKES.
